William G. H. Finch, New York, N. Y.

Application December 4, 1935, Serial No. 52,871

12 Claims. (Cl. 178—4)

My invention relates to electronic distributors useful in signalling systems, and more particularly, relates to the application of an electron beam distributor for high speed printing telegraph operation.

Modern high speed printing telegraph systems operate with a Baudot or five unit code. A continuous tape is successively punched with a predetermined combination of holes for each character. It is the practice to pass the tape through apparatus having five mechanical feelers which in turn operate contactors connected to contact plates on a mechanical distributor. The mechanical distributor, as is well known in the telegraph art, comprises a rotating arm for successively contacting the contact plates to transmit coded impulses in succession. The operation of mechanical distributors materially limits the speed of transmission of printing telegraph signals.

It is accordingly the main object of my present invention to eliminate the mechanical distributor and substitute therefor an electronic distributor. The electron beam of a cathode ray tube is made to scan a plurality of metallic plates or targets corresponding to the individual contacts of a mechanical distributor. The substitution of an inertialess selector for the mechanical selector in a distributor makes possible accurate transmission of telegraphy signals at much higher speeds than heretofore possible. A receiver is arranged having an electronic distributor similar to that of the transmitter and selects the transmitted code signals to operate standard telegraph printing apparatus.

It is accordingly an object of my invention to provide a novel high speed signalling system.

Another object of my invention is to provide a novel electronic distributor to replace the mechanical distributor in printing telegraphy systems.

Still another object of my invention is to provide a novel means for synchronizing the operation of transmitter and receiver distributors in signalling systems.

A further object of my invention is to provide novel methods of and means for high speed transmission of coded signals successively punched in a perforated message tape.

These and other objects of my invention will become apparent in the following description in connection with the drawings, in which:

Figure 1 is a schematic illustration of one embodiment of a transmitting telegraphy system

employing an electronic distributor according to my invention.

Figure 2 is a schematic illustration of a receiver for translating the printing telegraphy signals transmitted according to Figure 1.

Figure 3 is another modification of an electronic distributor used in the transmission of printing telegraphy signals.

Figure 4 is a schematic illustration of a receiver corresponding to the transmitter of Figure 3.

Figure 5 is a further modification of a printing telegraph transmitter according to my invention.

Figure 6 is a schematic illustration of a receiver for use with the transmitter of Figure 5.

In carrying out my invention, I employ an electron beam 10 produced in a highly evacuated vessel 11. The generation of the electron beam is familiar to those skilled in the electronic art and is schematically shown in Figure 1. The cathode 12 is heated by the heater 13 which is connected to suitable battery supply. The first anode 14 concentrates the emitted electrons into an electron beam. The high voltage anode 15 accelerates the electrons of the beam 10 which passes between the electrostatic deflecting plates 16, 17, 18 and 19 and on to the opposite end 20 of the vessel 11.

A high voltage direct current potential source 21 supplies the operating potentials for the electrodes of the cathode ray tube 11. A potentiometer 22 is connected across the battery 21. The second or high voltage anode 15 is connected to the positive side 23 of the potentiometer 22 which point is connected to ground in my preferred embodiment. The first anode 14 is connected to a suitable intermediate potential by tap 24. The control grid 25 is negatively biased with respect to the cathode 12 by a suitable tap 26 of the potentiometer 22. Deflecting plates 16 and 18 are connected to the grounded high potential point 23 to assume the same potential as the anode 15. The plates 17 and 19 are connected to ground through high resistances 27 and 28 so that the electrostatic deflecting plates and the anode 15 have a common static potential which is at ground potential, an operating expedient commonly employed.

On the back face 20 of the tube 11, I arrange a plurality of metallic plates or targets 29 within the tube. As illustrated in Figure 1, these plates 29 are spaced around a circle within the tube 11 and have connections projecting through the tube at points 30. Five of the metallic electrodes 29

are connected to corresponding contactors 31 of a selector mechanism 32. In modern printing telegraphy, a message tape, if employed, has a succession of holes punched according to a predetermined code. The commonly used Baudot code, for example, employs combinations of five units to correspond to individual letters or symbols. The punched tape is passed through a selector mechanism which has five feelers which 10 coat with the tape and operate contactors 31 as is well known in the art. I have schematically illustrated such a selector mechanism at 32.

The contacts of the contactors 31 are connected in parallel across the input circuit 33 of a thermionic amplifier stage 34. The output 35 of the amplifier 34 is connected to a modulator 36 for modulating a radio frequency carrier produced by the radio frequency oscillator 37 connected to the radio frequency amplifier 38 to be transmitted for radio transmission by the antenna 39.

A local oscillator 40 is connected to the electrostatic deflecting plates 17 and 19 through a rotator circuit 41 comprising a condenser 42 and resistance 43 connected as shown. The impedance of the condenser 42 is adjusted to be substantially equal to the resistance 43 at the frequency of the local oscillator 40. The electron beam 10 will be moved in a circular path as is well known in the art. The diameter of this circular path 44 at the end 20 of the tube 11 depends upon the voltage output of the oscillator 40 which is adjusted so that the diameter of the path 44 coincides with the mean diameter 25 of the circularly arranged plates 29. I thus provide means for successively scanning the electrodes 29 at a predetermined rate.

When the electron beam 10 impinges on a target 29, the electrons will be conducted to ground through its corresponding contactor 31 if it is not actuated by its selector feeler, but connects to the lower contact. However, if a feeler of the selector mechanism 32 at that time projects through a hole in the perforated tape, 45 an arm of the corresponding contactor, for example, 31a, will be moved to connect to its upper contact point 45 and the electrons of beam 10 impinging on the corresponding target 29a will be conductively connected to the grid 46 of the thermionic amplifier 34. The electrons of the beam 10 are attached to ground since the high potential side of its accelerating battery source 21 is connected to ground. The electrons of the beam 10 accordingly pass to ground through the input circuit or grid resistor 38. The electrons flowing through the grid resistor 38 produce a potential change upon the grid 46. A corresponding impulse is transmitted through the amplifier 34 to its output 35. Accordingly, while the electron beam 10 is passing over an electrode 29 having its corresponding contactor 31 actuated by a selector feeler projecting into a hole in the perforated tape, electrons will be conducted to the input circuit 33 of the amplifier 34 and produce a pulse or signal therethrough. This pulse or signal is introduced to the modulator 36 for radio transmission as described.

The operation of the electronic distributor according to my invention therefor is to cause an electron beam 10 to successively scan a plurality of metallic target electrodes 29 arranged at the far end of the evacuated envelope 11. The electrodes 29 are connected to individual contactors 31 of a selector mechanism 32 of a perforated tape telegraphy system. Each contactor 31 and

its corresponding electrode 29 corresponds to a predetermined component of the five unit code of the perforated tape. With each symbol group punched in the tape, a corresponding arrangement of contactors 31 will be actuated to their upper contacts during the transmission of the code group. The frequency of the oscillator 40 is adjusted so that it successively scans all the electrodes 29 once for each code group advanced through the selector mechanism 32. Each contactor 31 actuated by a hole in the perforated tape conductively connects its corresponding electrode 29 to the grid 46 of the amplifier 34, and a signal pulse will be produced by the amplifier 34 when the electron beam 10 passes over this target 15 29. Accordingly, a succession of signal pulses is transmitted corresponding to the code group on the perforated tape being presented to the mechanical feelers in the selector mechanism.

The selecting mechanism feeds the perforated tape at a predetermined rate in accordance with the frequency of scanning of the electrodes 29 and each code group is retained by the selector pins during the execution of each cycle of scanning. The electron beam will therefore be conductively connected to the grid 46 of the amplifier 34 as it successively scans the electrodes 29 in accordance with the code group being transmitted. The oscillator 40 is connected to the modulator 36 by leads 47. The radio frequency carrier wave which is radiated by antenna 39 is modulated by the signal impulses and by the scanning frequency. The purpose of transmitting the scanning frequency from oscillator 40 is to provide accurate synchronization for the electronic distributor at the receiver.

The advancement of the perforated message tape, through the selector mechanism 32 is synchronized with the scanning movements of the electron beam 10 over the targets 29. The tape 40 is retained in the selector mechanism during the scanning operation of a code group and is advanced to the next code group at the end of each cycle. The actuating means for the stepping of the tape through the selector mechanism 45 is preferably an electro-magnetically operated pawl and ratchet arrangement schematically shown as 32a. I provide a sixth target electrode 29b, which is connected directly to the stepping mechanism 32a. A signal amplifier is included in the electro-magnetic unit 32a to sufficiently amplify the impulse to operate the mechanical stepping means. The electrode 29b sets off the five signal targets 29 into one group. At the end of a code group transmission, therefore, 55 the electrode 29b is impinged by beam 10 and the electromagnetically operated stepping mechanism automatically advances the message tape to the next code group to be transmitted. The cycle is then repeated. The rate of transmission 60 of the code groups is accordingly predetermined by adjusting the frequency of the oscillator 40, the number of groups transmitted per second being equal to the generated cycles per second of the oscillator 40.

The target 29b is also connected to the input circuit 33 of the signal impulse amplifier 34 through a unidirectional impedance device 48. 48 may be a buffer stage of thermionic amplification, or a rectifier. A unidirectional impedance 48 is used to transmit an electron beam 10 impulse at target 29b to the signal amplifier 34, but to prevent any signal impulses from other targets from reaching the stepping amplifier 32a. The stepping mechanism 32a will there- 75

fore be actuated only by the impulses on target 29b for proper action thereof. The impression of the impulse of target 29b upon the signal amplifier 34 is to transmit, at the end of each cycle, an impulse to be utilized at the receiver as a "printing impulse". The function of the "printing impulse" will be described hereinafter in connection with the receiver printing mechanism.

In Figure 2, I have illustrated receiving apparatus for use in conjunction with the transmitter of Figure 1. The receiving antenna 49 is connected to the radio receiver 49' which detects and amplifies the telegraphy signals. A filter 50 is connected to the output of the receiver 49 and is tuned to the scanning frequency generated at the transmitter by the oscillator 40. The output of the filter 50 is introduced to an amplifier 51 which is connected to the electro-static deflecting plates 53 and 54 through the rotator circuit 52. Their corresponding deflecting plates 55 and 56 are connected to ground potential. The second anode 57 is also connected to ground potential as is the positive terminal of the high voltage direct current source 58. The operating potential of the first anode 61 is adjusted with the tap 62 of the potentiometer 60. Resistors 63 and 64 having high resistance, connect the deflecting plates 53 and 54 to ground.

The receiver electronic distributor 65 is of similar construction to that of the transmitter of Figure 1. An electronic beam 66 is produced and caused to scan a plurality of metallic electrodes or targets 67 arranged in a circular path on the back wall 68 of the evacuated envelope. The targets 67 are individually connected to amplifiers 69 at the outputs of which are connected relays 70. There are five relays 70 which are used to operate a local printing telegraph. The output of the receiver 49 is connected to a transformer 71 the output of which is impressed across the grid 72, and cathode 69. The grid 72 bias potential is adjusted to a suitable negative value by the potentiometer 73 connected across the grid biasing battery 74.

The synchronizing frequency impressed across the electrodes 53 and 54 through the rotator circuit 52 produces a rotation of the electron beam 66. The voltage output of the amplifier 61 is preferably adjusted to produce a path diameter 75 of the electron beam 66 about equal to the mean diameter of the circularly arranged targets 67. The operating potentials of the electrodes are adjusted so that the beam 66 will be properly focused to impinge upon the targets 67 when a signal impulse is impressed upon the grid 72. The bias of the grid 72 is adjusted so that when no signal impulse is transmitted through the transformer 71, it will be sufficiently negative to throttle the electron beam 66 and prevent it from reaching the electrodes 67. Accordingly, the electron beam 66 moves in the circular path 75 at a predetermined rate equal to the rate of beam 10 at the transmitter. In the embodiment of Figure 2, the signal impulses will bring the electron beam 66 into proper focus upon the electrodes 67, but during "no signal" the negative potential of the grid will be such as to throttle the beam 66 to prevent its reaching the electrode 67. When the electron beam 66 impinges upon a target 67, a pulse is introduced to the input of the corresponding amplifier 69. The production of the pulse by the electron beam 66 at the amplifier 69 input is the same as the production of the signal impulse introduced at

the grid 46 of the amplifier 34 of Figure 1 described hereinabove. The amplifiers 69 are made sufficiently sensitive to suitably energize the corresponding relays 70 for actuating the local printing mechanism.

The phase of the scanning signal filtered at 50 and introduced to the amplifier 51 is adjusted by well known phase shifting means, schematically indicated at 76, to cause the electron beam 66 to pass over predetermined targets 67 in synchronization with the corresponding targets at the transmitter in order to maintain the code combinations for the printing mechanism. Therefore, when the electron beam 10 of the transmitter impinges on the electrode 29a, the receiver electron beam 66 will impinge upon the corresponding electrode 67a to actuate the printing relay 70a, in proper sequence. Once the beam 66 is adjusted in proper phase relation with the transmitted impulses, the electronic distributor according to my invention will continue to be in synchronism with the transmitter and operate to selectively print the letters or symbols which are selected by the mechanism 32 of the transmitter according to the coded punchings in the perforated tape passing therethrough.

A sixth target 67b is included in the target group of the receiver electronic distributor 65, and corresponds with the target 29b at the transmitter. A "printing impulse" is transmitted at 30 the end of each code group as hereinabove described, corresponding to the target 67b. Accordingly, an impulse will be impressed through target 67b upon the amplifier 69b to actuate a "printing impulse" relay 70b. The printer relay 35 70b may be employed to directly print the character selected by the other five relays 70, or may function to transfer the code group set up to another group of magnets or selectors provided in a manner well known in the art. The relays 40 70 will thereafter be reset in readiness for the next code group transmitted.

The scanning frequency in cycles per second is equal to the rate of transmission of code groups per second. There is no inertia, mechanical wear, sparking or dust troubles with the electronic distributor according to my invention. A greatly increased speed of operation is possible with my system as compared to existing printing telegraphy systems employing mechanical distributors.

Other methods of synchronization are feasible for the electron distributor. A local oscillator at the receiver may be used to scan the electron beam across the targets. The frequency of this local oscillator may be synchronized or interlocked with the transmitting oscillator by methods familiar to those skilled in the communications arts. The system illustrated in Figures 3 and 4, embody such synchronization, and like numerals correspond to similar components in Figures 1 and 2.

The transmitter of Figure 3 differs from Figure 1 in the omission of the connecting leads 41 from the scanning oscillator 40 to the modulator 65 36. The scanning signal is accordingly not transmitted. The "printing impulses" produced by electrode 29b are utilized at the receiver for its local oscillator synchronization. The system embodied in the schematic illustration of Figure 3, produces a succession of impulses according to the five unit coded character being transmitted, plus an additional pulse which is always transmitted at the end of each code group. A series of regularly timed synchronizing impulses 75

are accordingly transmitted, one pulse corresponding to each cycle executed by the local oscillator 40.

Figure 4 is a schematic illustration of a receiver for the transmitter described in connection with Figure 3. There are six electrodes 67. The synchronizing electrode 67b corresponds to the electrode 29b of Figure 3. A local oscillator 77 generates sinusoidal waves. The output of the oscillator 77 is introduced to the rotator circuit 52 connecting across the deflecting plates 53 and 54 to produce the rotation of beam 66 in the circular path 75. The local synchronizing impulse is obtained when the electron beam 66 impinges on the electrode 67b. The electron impulse is introduced to the pulse amplifier 78, the output of which is connected to the local oscillator 77. The frequency of the local oscillator 77 is adjusted close to that of transmitter oscillator 40. The synchronizing impulses introduced by amplifier 78 to the oscillator 77 interlock or synchronize it with the transmitting oscillator 40 to cause it to generate the same frequency as the oscillator 40 of the transmitter. The interlocking arrangement for synchronization of two oscillators is familiar to those skilled in the communications art and is not described in the present disclosure.

The operating potentials of the electrodes are adjusted so that the beam 66 is properly focused upon the targets 67 and is rotated in the circular path 75 in synchronism with the transmitter beam 10. I have illustrated in Figure 4 a modified method for causing the beam 66 to impinge on the proper targets 67 during the signal pulses. The output of the receiver 49' is connected to the transformer 71, the output of which is connected in series with the high potential terminal 78 of the high voltage source 58 and ground. The signal impulses accordingly, alter the deflectional sensitivity of the electron beam. The signals are polarized so that during a signal impulse, the beam 66 is made more sensitive to the rotator voltage, and reaches the indicated path 75 to move across the targets 67. During no signal impulse, the electron beam 66 rotates in a path smaller in diameter than 75 and does not impinge on the electrodes 67; producing no actuation of corresponding relays 70. The signal impulses transmitted by the system according to Figure 3 are detected and amplified by the receiver 49' of Figure 4 and impressed upon the electrodes of the electronic distributor 65 to alter the deflectional sensitivity of the beam 66. A signal impulse permits the beam 66 to travel in the normal path 75, the diameter of which is determined by the frequency and voltage produced by the local oscillator 77. There is one synchronizing impulse per code group or cycle of operation, which impulse is received by the electrode 67b, amplified by 78, and used to interlock or synchronize the local oscillator 77 with the transmitter oscillator 40. Whenever a signal impulse is impressed on the apparatus, the beam 66 is caused to impinge on the proper target 67 and a signal impulse will be impressed upon the input of a corresponding amplifier 69. A printer relay 70 is connected at the output of the amplifier 69. When no signal impulse is received, the beam passes around the corresponding target 67 and no impulse is impressed upon its associated amplifier 69, leaving the corresponding relay 70 unactuated. A succession of combinations of five on and off signals will set up 75 the predetermined letter or character selected by

the transmitter selector mechanism 32 at the local printing apparatus.

The synchronizing electrode 67b is also connected to the amplifier 69b at the output of which is connected a "printing impulse" relay 70b. The synchronizing impulses will accordingly also operate printing of the set-up character and reset the relays 70 for the next code combination.

It is not necessary for the targets to be arranged in a circular path. In the further modification schematically illustrated in Figure 6, I have illustrated the targets 67 at the receiver arranged in a linear path 75'. The scanning of the electron beam 66 produced by a linear or sweep circuit oscillator is normally in a straight line as is well known in the art. At one end of the linearly arranged electrodes 67 there is placed the synchronizing electrode 67b connected directly to the pulse amplifier 78. The output of the amplifier 78 is connected to the sweep circuit oscillator 77' to interlock or synchronize its frequency with that at the transmitter. The output of the sweep oscillator 77' is connected directly to the electrostatic deflecting plate 64 to cause the beam to normally traverse the linear path 75' across the targets 67.

The signals received by receiver 49' are detected, amplified and directly impressed upon the deflecting plate 53. The output of the receiver 49' is polarized so that when no signal is impressed upon it, the action of the deflecting plates 53-55 is to deflect the beam away from the path 75' through the targets 67. When a signal impulse is received, the beam is moved back to the path 75' to impinge upon a predetermined target 67. It is not necessary in this embodiment of Figure 6 to impress the received signal impulses upon the deflecting plate 53. This plate 53, may for example, be grounded and the signals be impressed upon the grid 72 or the anode as in the previously described modifications.

As the beam 66 traverses the targets 67, signal impulses cause it to impinge upon predetermined targets 67 which are directly connected to amplifiers 69. The beam 66, accordingly produces an impulse at the input of the corresponding amplifier 69 to actuate a printing relay 70'. There are five such printing relays 70' illustrated. These relays operate local selector mechanisms 80 for printing telegraphy operation. It is preferable that the transmitter corresponding to the receiver of Figure 6 be similarly arranged with linearly disposed targets 29 and have a sweep circuit oscillator for linear scanning of the electron beam. Figure 5 is a schematic illustration of such a transmitter. However, I illustrate in Figure 5 a transmitter employing a novel optical method for scanning perforations in the message tape. If a selector mechanism similar to 32 of Figure 3 is to be used, the electrodes 29 are arranged exactly as shown in Figure 6 along a straight line instead of in a circular path.

In Figure 5 I illustrate an optical method for producing the succession of impulses required to operate the receiver described in connection with Figure 6. The electrodes of the tube 11 and their operating potential connections and sources are identical with those in Figures 1 and 3 and are labelled with similar numerals. The oscillator 40' is a linear or sweep circuit oscillator 70 and is connected to the deflecting electrode 17. The electron beam 10 passing between the deflecting plates 16 and 17 is accordingly swept across the linear path 81 on the fluorescent screen 82 at the opposite face of the cathode ray oscil-

graph. A travelling spot of light produces the visible line 81.

The perforated message tape 83 is arranged on rollers 84 and 85. One of the rollers 85 is connected to an electrically operated mechanical advance mechanism 86. The mechanism 86 may be a simple electro-magnetic pawl and ratchet arrangement actuated directly from the local linear oscillator 48 and connected thereto by leads 47. The mechanical advancing means 86 is actuated once per cycle of the scanning frequency, and is accordingly arranged to advance the tape 83 one notch or code groups at the end of each scanning operation by electron beam 10. The electron beam 10 impinges upon the fluorescent screen 82 along the linear path 81 directly in front of a code group being scanned.

The illustration of Figure 5 shows six perforations being scanned corresponding to a predetermined symbol to be transmitted. Each perforation permits the moving light spot to impinge therethrough upon a photo-electric cell 87. A suitable lens 88 may be used to direct the light passing through the perforations to the photo-electric cell 87. There is, accordingly, in the illustrated code group being scanned, a series of six consecutive light impulses impressed upon the photo-electric cell 87. The photo-electric cell 87 is connected to a suitable amplifier 84 which in turn is connected to the modulator 36 for modulating the radio transmitter system composed of the radio frequency oscillator 37, radio frequency amplifier 38 and antenna system 39. The perforations illustrated at the left edge of the tape 83 correspond to the synchronizing impulses of the previous modifications. Accordingly, at the end of each code group transmitted, there is always a corresponding synchronizing impulse also transmitted for interlocking or synchronizing the oscillator at the receiving station in a manner already described. The transmitter of the type of Figure 5 is preferably used in conjunction with the receiver of Figure 6 having linearly disposed electrodes 67.

Having described in detail several embodiments of electronic distributing systems, many modifications thereof which fall within the broader spirit and scope of my invention will be evident to those skilled in the art. Thus, the various components in any particular practical application of my invention may have optional arrangements. Variations may be made in: the manner of producing the electron beam; the path of motion of the electron beam; the arrangement of the target electrodes; the type of scanning oscillator and synchronizing methods; the method of transmission such as over a wire line or by radio; the method of deflecting the scanning beam from the receiver target electrodes according to signal impulses; or in the type of local printing mechanism and actuation employed. I have illustrated electrostatic means for deflecting and controlling the electron beam. Electro-magnet deflecting means may, however, equally well be employed.

I have in the foregoing described the application of the electronic distributor in connection with five unit code for a printing telegraph. It will be understood that I do not intend to be limited to such applications of the electronic distributor. A plurality of target groups may be arranged in one tube for use with multiplex telegraph systems analogous to a similar application with mechanical distributors now employed. Although I have described unidirectional impulses

for each signal, it will be understood that each signal impulse may be made intermittent or may comprise a plurality of successive impulses operating during the interval of the traverse of the beam across a particular target. The intermittent nature of a signal impulse may have no particular significance as far as signal intelligence is concerned, or may comprise a signal group for further subdivision at the receiver so that one group letter will correspond to the intermittent traverse of the electron beam over a single target. Still further modifications are possible and I do not intend to be limited in the application of my invention except as set forth in the following claims.

I claim:

1. In a printing telegraph system, selector mechanism for setting up code combinations of signals to be transmitted; said selector mechanism comprising a plurality of contactors, each having a marking and a spacing signal position; an electronic distributor connected to said selector mechanism for transmitting the signals set up on said selector mechanism in accordance with a predetermined sequence; and means controlled by said electronic distributor for periodically controlling said selector mechanism to set up a new code combination of signals for each cycle of operations of said electron stream.

2. In a signalling system, a transmitter comprising a plurality of contactors; means for selectively operating said contactors; an electron distributor comprising a plurality of targets, an individual target being connected to each of said contactors, means for generating an electron beam, and means for cyclically scanning said targets with said beam; a transmitting channel; means for impressing code combinations of signal conditions on said channel in accordance with the operation of said contactors as said beam impinges on said targets; and means including one of said targets for impressing a predetermined cyclic signal condition on said channel.

3. In a signalling system, a transmitter comprising a plurality of contactors; means for selectively operating said contactors comprising a perforated tape; an electron distributor comprising a plurality of targets, an individual target being connected to each of said contactors, means for generating an electron beam, and means for cyclically scanning said targets with said beam; a transmitting channel; means for impressing code combinations of signal conditions on said channel in accordance with the operation of said contactors as said beam impinges on said targets; and means including one of said targets for impressing a predetermined cyclic signal condition on said channel.

4. In a signalling system, a transmitter comprising a plurality of contactors; means for selectively operating said contactors comprising a perforated tape; an electron distributor comprising a plurality of conductive targets, an individual target being connected to each of said contactors, means for generating an electron beam, and means for cyclically scanning said targets with said beam; a transmitting channel; means for impressing code combinations of signal conditions on said channel in accordance with the operation of said contactors as said beam impinges on said targets; and means including one of said targets for impressing a predetermined cyclic signal condition on said channel.

5. In a printing telegraph system, a transmit-

current source; a transmitting channel; means for impressing code combinations of signal conditions on said channel in accordance with the operation of said contactors as said beam impinges on said targets; means including one of said targets for impressing an operating signal condition on said channel; means including said source for impressing a synchronizing signal condition on said channel; a receiver connected 5 to said channel comprising an electron distributor 10 having a plurality of targets corresponding to the

said transmitter targets and an electron beam operable over the receiver targets; means responsive to said synchronizing signal condition for maintaining the receiver beam in synchronism with the transmitter beam; selector mechanism connected to receiver targets for translating the code signal conditions; and means connected to one of the receiver targets and responsive to said operating signal condition for controlling said selector mechanism. 5

WILLIAM G. H. FINCH. 10
